(57) **CLAIM**

The ornamental design for a combined knife holder and cutting board, as shown and described.

DESCRIPTION

FIG. 1 is a perspective view of a combined knife holder and cutting board showing our new design;

FIG. 2 is a front view thereof;

FIG. 3 is a side view thereof, the opposite side view being a mirror image thereof;

FIG. 4 is a back view thereof;

FIG. 5 is a top view thereof;

FIG. 6 is a bottom view thereof; and,

FIG. 7 is a perspective view thereof, shown in opened condition.

The broken lines in the figures illustrate environmental subject matter that form no part of the claimed design.
